(57) **CLAIM**

The ornamental design for a stabilizing stud mount, as shown and described.

DESCRIPTION

FIG. 1 is a side elevational view of a stabilizing stud mount showing my new design of the present invention;

FIG. 2 is a side elevational view thereof taken from the right side of FIG. 1, it being understood that the opposite side is a mirror image thereof;

FIG. 3 is a bottom view thereof; and,

FIG. 4 is a top plan view thereof.
